UNITED STATES PATENT OFFICE.

HUGH D. SMITH, OF RICHMOND, VIRGINIA.

IMPROVEMENT IN PLOWS.

Specification forming part of Letters Patent No. **158,186**, dated December 29, 1874; application filed May 9, 1874.

To all whom it may concern:

Be it known that I, HUGH D. SMITH, of Richmond, in the county of Henrico and State of Virginia, have invented a new and useful Improvement in Plows, of which the following is a specification:

Figure 1 is a side view of a plow illustrating my improvement. Fig. 2 is a detail section taken through the line *xx*, Fig. 1. Fig. 3 is a side view of a modification of the same. Fig. 4 is a top view of the same.

Similar letters of reference indicate corresponding parts.

The invention will first be fully described, and then pointed out in the claim.

A represents a plow-beam, to the side of which is securely attached a cleat, B, in a notch or groove in which the forward or lower edge of the plow-standard C rests and slides, and against which it is locked by a cleat, D, placed upon the rear or upper side of the said standard, and which is notched or grooved to fit upon said standard C, and enter a notch in its rear side. Several notches are formed in the standard C, to receive the cleat B and hold the beam securely, however it may be adjusted. The cleat D is held down upon the standard C by a bolt, E, which passes through the said cleat D, and through the cleat B, or the beam A, and which is provided with a hand-nut, to enable it to be conveniently tightened and loosened. As shown in Fig. 1, the standard C is inclined forward, so as to bring the beam A low down. The lower part of the

standard C passes back of the mold-board F, is curved downward upon the arc of a circle, and is attached to, or formed upon, the land-side G, thus forming an opening narrower in its upper part and wider in its lower part, so that any light trash that may not be pressed downward upon the furrow-slice, and turned under by said furrow-slice, may drop through the opening between the standard C and mold-board F into the furrow, to be covered by the next furrow-slice.

The construction of the beam-adjusting device must be varied according to the construction of the plow to which it is to be applied. Figs. 3 and 4 show it applied to a vertical standard.

By this construction, by loosening the nut of the bolt E, and moving the cleat D out of the notch of the standard C, the beam A may be moved up or down upon said standard, the cleat B keeping it always parallel with its former position.

Having thus described my invention, I claim as new and desire to secure by Letters Patent—

The combination of the stationary cleat B, the pivoted cleat D, and the bolt E with the plow-beam A and the notched standard C, substantially as herein shown and described.

HUGH D. SMITH.
